UNITED STATES PATENT OFFICE.

JAMES HOLMES, OF FRANKLIN, INDIANA.

DEVICE FOR FILLING GRAVES.

SPECIFICATION forming part of Letters Patent No. 226,856, dated April 27, 1880.

Application filed February 2, 1880.

To all whom it may concern:

Be it known that I, JAMES HOLMES, a citizen of the United States, residing at Franklin, in the county of Johnson and State of Indiana, 5 have invented certain new and useful Improvements in Devices for Filling Graves; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 Figure 1 is a perspective view of my invention. Fig. 2 is a longitudinal sectional view of the same. Fig. 3 is a side view, partially broken away to show the handle K. Fig. 4 is a bottom view of the dump-car.

20 This invention relates to that class of devices for holding the soil displaced by digging the grave and depositing such soil upon the coffin.

The improvements consist in the novel construction of the frame, having an inclined track extending downwardly to the front or deposit end of the frame, and having side pieces with double inclines to support or guide the side journals of the car, whereby the 25 car is moved slowly, then at a quick speed as it assumes the vertical position.

The novelty also consists in providing the rear end of the car-platform with rollers or wheels to transport the device over the ground, 30 in combination with a handle, as will be hereinafter more fully set forth and pointed out in the claims.

In the annexed drawings, forming a part of this specification, the letter A represents a 35 frame or platform composed of two side bars, B B, and transverse bars D and D'.

To the inner sides of the side bars, B B, are suitably secured inclined tracks E E, (only one shown in Fig. 2,) the lower portions of 40 which are inclined toward the front or dumping end of the frame.

The rear ends of the inclined track are suitably braced by means of the bars D D' and the front ends by means of the beveled bar D², substantially as shown in Fig. 2 of the 45 drawings.

The rear end of this frame A is provided with rollers or wheels F F, for the purpose hereinafter stated.

The side bars, B B, are formed with the 55 double-inclined surfaces a b and the stops c, as shown in Fig. 1 of the drawings.

The letter H represents the dump-car, the bed-frame of which is provided with four flanged wheels suitably journaled therein. 60

The upper portion of the car platform or floor is provided with detachable back and side pieces, I, having standards d fitting in sockets e of the platform. This car is also formed with side journals, J, arranged centrally on the sides of the car. 65

The wheels of the car-bed rest upon the tracks of the frame, and the side journals rest on the incline surface of the side bars.

By this arrangement of the parts it will 70 be seen, by reference to the drawings, that the frame A, with its dump-car, is placed upon the ground, the front end facing the grave to be dug, and the soil displaced by digging is thrown into the car. After the coffin is lowered into the grave the car is moved upon the inclined tracks and guideways, assuming a vertical position, (see Fig. 2,) to deposit the 75 soil upon the coffin and fill the grave. This method of filling the grave shortens the 80 mournful service at the grave and does not mar the surrounding ground and grass.

The front end of the frame is provided with a detachable rod, K, which serves as a handle (see Fig. 3) in transporting the device 85 over the grounds.

The advantages of these improvements are obvious, and further description seems unnecessary.

What I claim is—

1. The combination of the frame or platform A, having inclined tracks E extending downwardly to the deposit end of the frame, and side pieces, B, with double inclines and stops, and the dump-car, mounted on wheels 95 or rollers provided with centrally-arranged side journals, substantially as and for the purpose set forth.

2. The portable grave-filling device, having at its rear end the rollers F and at its 100 forward end the cross-bar K, serving as a handle, substantially as described.

In testimony whereof I affix my signature in presence of two witnesses.

JAMES HOLMES.
